UNITED STATES PATENT OFFICE

RENÉ LALIQUE, OF PARIS, FRANCE

DESIGN FOR A BOTTLE

Application filed December 4, 1928, Serial No. 29,102, and in France November 8, 1928. Term of patent 14 years.

To all whom it may concern:

Be it known that I, RENÉ LALIQUE, a citizen of the Republic of France residing at 40 Cours Albert 1er, Paris, France, have invented a certain new, original, and ornamental Design for Bottles, of which the following is a specification, reference being had to the accompanying drawing, forming part thereof.

In the said drawing:

Fig. 1 is an elevation view of a bottle in accordance with the invention,

Fig. 2 is a top plan view of the same.

The bottle is made of cristal, glass or other similar materials.

I claim—

The ornamental design for a bottle substantially as shown.

In testimony whereof I have affixed my signature.

RENÉ LALIQUE.
